UNITED STATES PATENT OFFICE

161,303

EXPANSIBLE BRACELET OR THE LIKE

Joseph M. Bender, Manhasset, N. Y., assignor to
Jacoby-Bender, Inc., New York, N. Y., a corpora-
tion of New York

Application March 2, 1949, Serial No. 1,174

Term of patent 7 years

(Cl. D45—4)

To all whom it may concern:

Be it known that I, Joseph M. Bender, a citizen of the United States and a resident of Manhasset, county of Nassau and State of New York, have invented a new, original, and ornamental Design for an Expansible Bracelet or the like, of which the following is a specification, reference being had to the accompanying drawing, forming a part thereof, in which:

Fig. 1 is a top plan view of an expansible bracelet embodying my new design, the conventional connecting links being shown in broken lines;

Fig. 2 is a side elevational view of the bracelet with the connecting links omitted for convenience of illustration and with the conventional bottom links shown in broken lines;

Fig. 3 is a top plan view of the bracelet with the connecting links omitted, illustrating the links in an expanded position;

Figs. 4 and 5 are enlarged bottom and side elevational views, respectively, of the symmetrical center link; and

Figs. 6 and 7 are enlarged left and right side elevational views, respectively, of one of the left-hand asymmetrical links.

I claim:

The ornamental design for an expansible bracelet or the like, as shown and described.

JOSEPH M. BENDER.
